CLAIM

The ornamental design for data transmission modem or
similar article, as shown and described.

DESCRIPTION

FIG. 1 is a right side elevational view of data transmission
modem or similar article showing my new design;
FIG. 2 is a left side elevational view thereof;
FIG. 3 is a front elevational view thereof;
FIG. 4 is a rear elevational view thereof;
FIG. 5 is a top plan view thereof;
FIG. 6 is a bottom plan view thereof; and
FIG. 7 is a top, front, right side perspective view
thereof on a reduced scale.

FIG. 1

FIG. 2

FIG. 3

FIG. 4

FIG. 5

FIG. 6

FIG. 7
